UNITED STATES PATENT OFFICE.

WILLIAM EDWARD WILLIAMS, OF ROOSEVELT, NEW YORK.

ELECTRIC GASOLINE GAUGE.

Application filed January 22, 1925. Serial No. 4,091.

This invention relates to electric gasoline gauges.

More particularly the invention relates to new and useful improvements in the class 5 of gauges or indicators for gauging or indicating the quantity of liquid in a remotely arranged tank, and has especial reference to the type of devices which employ electrical indicating means, which is operated by 10 mechanism responsive to the rise and fall of liquid within the tank.

One of the objects of the present invention is to produce an apparatus of the character mentioned which is efficient and 15 economical in use, and which has certain safeguards against explosion in cases where the same is used in connection with tanks containing explosive liquids such as gasoline.

Another object of the invention is to produce a device which is capable of being used 20 in conjunction with liquid tanks of different depths.

Another object of the invention is to produce a device of the character mentioned 25 which will be simple of construction and one which may be readily installed for use in connection with all forms of liquid tanks now in use as part of the equipment of automobiles.

With the foregoing and other objects in 30 view, the invention resides in the particular combination, relative disposition, and operation of the parts hereinafter fully described and illustrated in the accompanying drawings, in which

Figure 1 is a diagrammatic view of the electrical indicating means employed as a part of the apparatus.

Fig. 2 is a vertical sectional view through 40 a tank with all but the lamp casing of the apparatus shown applied to the tank.

Fig. 3 is a sectional view taken on the line 3-3 of Fig. 2.

Fig. 4 is a face view of the lamp casing, 45 which in use is arranged at a point remote from the tank and the other parts of the apparatus.

Fig. 5 is a transverse sectional view through the lamp casing shown in Fig. 4.

The invention, generally stated, consists 50 of a tank 10 which contains the liquid, indicating means 11 including a lamp casing which is arranged remote from the tank 10; and means 12 responsive to the rise and fall 55 of the liquid in the tank for actuating the indicating means 11.

The tank 10 may be of any suitable well known construction and has an opening 13 therein. The means 12 and parts of the indicating means 11 are attached to and supported by the top wall of the tank at the opening 13.

The indicating means 11 consists of the parts presently described. A casing 14 which carries electric lamps 15 is arranged 60 at a point remote from the tank 10. The casing 14 is subdivided by partitions 16 into compartments 17 over each of which is arranged a translucent plate. The plate 18 is "white" and has the word Full printed thereon, whereas the plate 19 is colored "red" 70 and has the words Get gas printed thereon and the plate 20 is colored "green" and has the word Half printed thereon. The casing 75 has attaching lugs which serve for the attachment of the casing. A circuit closer 21 is employed and consists of contacts 22, 23 and 24 which are arranged in an arc of a circle and are attached to a composite base 25 of 80 non-conducting material such as cork and fiber; and a contact 26 in the form of a segment arranged adjacent the contacts 22, 23 and 24 concentrically with respect thereto, the contact 26 being attached to said base; and a bridging member 27 in the form of 85 a roller which is rotatably carried by an arm 28 of insulating material such as fiber. Referring now more particularly to Fig. 1, it will be seen, that wires lead respectively from the contacts 22, 23 and 24 to the 90 lamps 15 and the wire from each lamp to one side of a source of electrical energy such as a battery 29 and that a wire also leads from the contact 26 to the other side of the battery with a switch 30 connected therein.

The means 12 before referred to specifically consists of a small shaft 31 having a crank 32 to which is connected an adjustable rod 33 pivotally connected by a pin and slot connection as at 34 to one end of a float arm 35 pivotally mounted as at 36 having a float 100 37 preferably of cork at the free end thereof. The arm 35 is adjustable by virtue of a turnbuckle 35'. The pin and slot connection is sufficiently loose to permit rod 33 to oscillate as the upper end thereof describes an arc because of the crank 32. The arm 35 is pivotally connected to an adjustable bracket 38 attached to a compound disk 39 of cork and metal which serves as a gasket 105 and partition over the mouth of a standard tank gauge connection 40 attached to the top 110

wall of the tank at the opening 13. The disk 39 carries a wall 41 in the form of a partition for the housing or casing 42. The wall 41 is made up from steel plates and an intermediate resilient gasket preferably of cork, all of which are bolted together as at 43. The housing 42 is preferably cylindrical and is adapted for threaded engagement with the connection 40 as at 44 and has a removable cap 45 at the upper end thereof. A gasket of cork is arranged between a portion of the cap and the upper end of the housing 42, and a portion of the cork gasket of the wall 41 extends up to and in sealing contact with the wall of the cap 45 to make the housing air tight. The shaft 31 is mounted for rotation in bearings or bushings 46 carried respectively by the wall 41 and the wall of the housing 42. The shaft 31 is of two parts and is coupled together as at 47. Collars 48 serve to prevent longitudinal movement of the shaft 31. It is to be noted that the disk 39, wall 41 and housing 42 constitute a mount for the float mechanism. 25 The circuit closer 21 is arranged in co-operative relationship to the means 12 by attaching the same as at 49 to a part 50 of the housing 42; the arm 28 carrying the roller 27 forming a part of the circuit closer 30 being attached to one end of the shaft 31 by a set screw 51 or the like. Suitable binding posts are employed in conjunction with the several contacts of the circuit closer for the proper connection of the wires between the 35 several parts to which they are respectively connected.

In the operation of the apparatus and with the float 37 in the position shown in Fig. 2, the roller 27 by virtue of the intervention of the several parts which connect it to the float, will bridge contacts 22 and 26 with the result that the lamp 15 in the compartment of the casing 14 behind the plate or panel 19 will be lighted to indicate 40 to a person that the supply of liquid in the tank should be replenished. As the liquid,

such as gasoline in the present instance, is put into the tank 10 the float 37 will rise causing the roller 27 to move to bridge the contacts 23 and 26 to light the lamp 15 in the compartment of the casing 14 behind the panel 20 to indicate that the tank is half full. Upon the increase of the amount of gasoline, the member 27 will be caused to bridge the contacts 24 and 26 with the result that the lamp 15 in the compartment of the casing 14 behind the panel 18 will be lighted to indicate that the tank is full. 55

In inventions of this type in which electrical means is employed in connection with gasoline tanks it is essential that safeguards be provided to prevent explosion caused by the presence of vapor of the gasoline at the contact forming part of the electrical means. For that reason in the present invention the disk 39, wall 41, and housing 42 are employed to provide an airtight chamber and to isolate the mentioned electrical contacts. An airtight chamber is also formed between the wall of the housing 42 and the base 25 of the circuit closer 21. By making the rod 33, arm 35, and bracket 38 adjustable or extensible the device may be operatively associated with tanks of different depths. 70

I claim:

In an apparatus for indicating the quantity of gasoline in a tank, the combination with the tank having an opening in the top wall thereof, of a housing detachably connected with the tank at its opening, removable partitions in said housing which combine with the walls of the housing to provide an airtight chamber therein, an adjustable bracket carried by one of said partitions, an adjustable float arm pivotally connected, with said bracket, a crank turnably supported by the other of said partitions and a wall of said housing, and an adjustable rod connected to said float arm and said crank. 85

WILLIAM EDWARD WILLIAMS.
